SYSTEM AND SAFETY DEVICE FOR MULTIPLE FURNACES

William A. Ray, North Hollywood, Calif., assignor to
General Controls Co., Glendale, Calif., a corporation
of California

Filed July 15, 1959, Ser. No. 827,218
7 Claims. (Cl. 158—131)

The present invention relates to an improved safety system for multiple furnaces supplied from the same fuel source and particularly to a common safety device sensitive to each of the flame-responsive means in a corresponding one of the multiple furnaces.

Oftentimes fuel is supplied from a single source to a plurality of heating units such as multiple fireboxes or combustion chambers. Since the fireboxes or combustion chambers are essentially individual units, the same are desirably monitored by a safety device which is sensitive to proper operating conditions in the firebox or combustion chamber; such proper operation condition may be, for example, the presence of a suitable pilot flame.

In accordance with prior practices, an individual thermocouple is associated with a corresponding firebox and the output of each of the thermocouples is applied to a corresponding safety device. This prior practice thus necessitates a separating safety device for each thermocouple. In accordance with an important feature of the present invention each of the thermocouples has its output applied to a single common safety device, thereby providing a simplified system which is less costly, more fool-proof and one in which there is produced a pressure drop through only one safety instead of a plurality of safeties as in prior systems.

For these purposes the system incorporates a novel safety device which involves generally a unitary magnetic structure on which is wound a plurality of coils, such coils being energized by a corresponding sensing device such as a thermocouple. The magnetic structure is such that an armature remains in an attracted position when all of the coils are energized but the force of attraction between the armature and the magnetic structure is insufficient to maintain the armature in attracted position when the current flowing through only one of such coils falls below a predetermined value.

It is therefore an object of the present invention to provide an improved safety system for multiple furnaces of the character indicated above.

A specific object of the present invention is to provide an improved magnetic structure operating in conjunction with thermocouples and energized with current from each of the thermocouples to maintain an armature in attracted position when each of the thermocouples is properly heated but which functions to allow the armature to be released when only one of such thermocouples is heated insufficiently.

Another object of the present invention is to provide an improved magnetic structure which is instrumental in achieving the new system outlined above.

Another object of the present invention is to provide an improved safety device responsive to a plurality of different conditions for effecting a control operation or indication when only one of such conditions fail to exist satisfactorily.

Another object of the present invention is to provide an improved magnetic structure for these purposes sensitive to a plurality of different conditions and operating such that when one of such conditions fails to exist satisfactorily, both a magnetic unbalance and a mechanical unbalanced condition exist to cause a control element to move with respect to said magnetic structure.

The features of the present invention which are believed

2

to be novel are set forth with particularity in the appended claims. This invention itself, both as to its organization and manner of operation, together with further objects and advantages thereof, may be best understood by reference to the following description taken in connection with the accompanying drawings in which:

FIGURE 1 is generally a sectional view through a safety control unit embodying features of the present invention.

FIGURE 2 is a sectional view taken substantially on the line 2—2 of FIGURE 1.

FIGURE 3 is a perspective view illustrating the coil and core structure in the device shown in FIGURE 1.

FIGURE 4 is another perspective view illustrating the core structure shown in FIGURE 3.

FIGURE 5 is a perspective view like FIGURE 4 but of a modified core structure arranged to have wound thereon three separate coils instead of two coils as in FIGURE 4.

FIGURE 6 illustrates a multiple furnace system embodying features of the present invention in which the safety device illustrated in FIGURE 1 is incorporated.

FIGURES 7 and 8 are generally enlarged sectional views illustrating the coaction between the movable armature and the core structure in the device shown in FIGURE 1; and FIGURE 8 illustrates the manner in which the armature may move with respect to the core structure when one of the multiple coils is de-energized.

FIGURE 9 is generally a sectional view taken in the direction indicated by the arrows 9—9 in FIGURE 3.

FIGURE 10 illustrates schematically electrical, magnetic and mechanical relationships of elements shown in the previous figures.

FIGURE 11 illustrates another modified structure in which the center leg 55A is flared instead of straight as in FIGURE 10.

The system shown in FIGURE 6, for purposes of simplicity, is illustrated as including only two fireboxes or furnaces 10 and 11, each supplied with fuel—in this case gas. The gas is applied to the inlet 12 of the safety control valve indicated generally at 13. This control valve 13 is shown in detail in FIGURE 1 and actually incorporates many different valves, such valves being the valve 14 defined by the valve seat 15 and its cooperating movable valve element 16; and the plug valve element 18 which controls the flow of fuel to the pilot burner outlet 19 and the main burner outlet 20. It will be seen that the valve 15, 16, when closed, prevents the flow of fuel to the outlets 19 and 20 regardless of the position of the plug valve element 18. For this purpose the valve 15, 16 is referred to as a safety valve and is controlled both manually and electrically as described in detail later.

The pilot outlet 19 supplies gas to each of the pilot burners 10A and 11A in the furnaces 10 and 11 respectively. The main burner outlet 20 is in communication with the main burners 10B and 11B in the furnaces 10 and 11. The flow of gases to such main burners 10B and 11B may be controlled by condition responsive or control means indicated generally at 10C and 11C respectively, and such condition responsive means may be responsive to various conditions such as, for example, temperature inside furnaces or temperature of a medium heated as a result of the fuel burned by the corresponding main burners. For purposes of simplicity, such condition responsive means are indicated generally as block diagrams in FIGURE 1 since it is well understood by those having knowledge of the art that such condition responsive means may take many different forms for many different purposes in accomplishing this general function of controlling the flow of gas to the burners.

Each one of the pilot burners 10A and 11A has associated therewith a suitable flame responsive means for

indicating the presence of the corresponding flame from the pilot burners; and as illustrated herein, such means comprises a corresponding thermocouple 10D and 11D heated by the corresponding pilot flame. The thermocouple 10D is connected to the coil 22 (FIGURES 1, 3, 9) of the magnetic structure 24; and the thermocouple 11D is connected to the coil 23 also wound on the same magnetic structure 24 so that current flows through these windings or coils 22 and 23 when corresponding thermocouples 10D and 11D are heated.

The construction of this magnetic structure 24, which includes the armature 25, comprises an important aspect of the present invention and is described in detail in connection with subsequent figures. This armature 25 operates magnetically with the stationary core structure 26 on which the aforementioned coils 22 and 23 are wound.

The armature 25, generally in the form of a disc, is loosely mounted on the pin 28 which carries the movable valve element 16 and which is slidably mounted in the wall 30 of housing 31. This armature 25 is normally biased downwardly in FIGURE 1 by the coil compression spring 32 which has one of its ends bearing against the stationary casing wall 30 and the other one of its ends bearing against the valve gasket retainer 34. This pin or stem 28 may be moved upwardly in FIGURE 1 manually by an operator using his finger to press the button 28A upwardly.

The operation of the system shown in FIGURE 1 is briefly as follows. In the "shut down" condition of the system the main safety valve 15, 16 is closed and the plug valve element 18 is in a position to disestablish communication between the passage 36 on the one hand and the outlet openings 19 and 20 on the other hand. This corresponds to the so-called "off" position of the manually operable knob 38 for positioning the plug valve element 18. In starting up the system, the knob 38 is rotated to a "pilot on" position wherein the passageway 36 is placed in communication with the pilot opening 19, and the button 28A is pressed upwardly to open the valve 15, 16 and to move the armature 25 into engagement with the core structure 26, in which case gas then flows in turn from the inlet opening 12, through the valve 15, 16 and through the opening 19 to both of the pilot burners 10A and 11A in the individual furnaces 10, 11. The button 28A is maintained manually in its upper position while the gas escaping from the pilot burners 10A, 11A is ignited and for a time sufficiently long thereafter to heat the associated thermocouples 10D, 11D, in which latter case the armature 25 is maintained magnetically by the core structure 26 without requirement of further manual effort.

When this condition is achieved, the operator may release the button 28A and the armature 25 remains retained against the core structure 26 to continue to maintain the valve 15, 16 open. As long as the pilot flames in furnaces 10, 11 continue to burn, they are, of course, effective to maintain the valve 15, 16 open and to ignite any gas escaping from the associated main burners 10B, 11B in response to one of many various conditions. Should, for any reason, there be a failure in one of the pilot flames, the associated thermocouple 10A, 10B cools down to a point where the core structure 26 is no longer effective to maintain the valve 15, 16 open, in which case this valve 15, 16 closes to thereby prevent the flow of gas to either one of the furnaces 10, 11. It should be carefully noted that the operation is such that the valve 15, 16 closes upon the extinguishment of only one pilot flame. A subsequent resetting operation involving manual operation of the button 28A as outlined above involves relighting of the two pilot burners.

As described in more detail later, the core structure 26 is such that it develops sufficient magnetic forces to maintain the armature 25 against such core structure only when both of the coils 22 and 23 are fully energized.

The desirability for shutting down both furnaces 10, 11 upon pilot burner failure in only one of the furnaces is quite evident upon consideration of the fact that both furnaces 10, 11 are usually vented to the same stack and that unburned gases flowing into said stack are apt to produce undesirable conditions and perhaps a minor explosion.

The device shown in FIGURE 1 incorporates means illustrated in FIGURE 2 for adjusting the size of the pilot flame. The means illustrated in FIGURE 2 is considered conventional and comprises simply an adjustable plug 40 threaded in a bore 41 to provide an adjustable restriction between the passageways 42 and 43 in the valve body 44, such passages leading to the pilot outlet port 19. Once the adjustable restricting plug 40 is adjusted, the cover 45 in the form of a screw-threaded plug is threaded in the bore 41 with a sealing gasket 46 between the cover 45 and the valve casing 44.

After the pilot burners function to maintain the armature 25 in its attracted position, the manual reset button 28A may then be released and the armature 25 will be maintained in its attracted position in engagement with the core 26 notwithstanding the action of the coil compression spring 30 which tends to move the armature 25 from its attracted position.

It will be understood that the reset mechanism involving the reset knob 28A is such that the knob 28A may return to its position shown in FIGURE 1 while the armature 25 is being maintained magnetically against the core 26. Further, it will be understood that the normal physical space between the armature 25 and the core 26 as shown in FIGURE 1 is such that the magnetism developed by the coils 22 and 23 (assuming that they are both fully energized) is insufficient to cause the armature 25 to be moved upwardly to its attracted position, but some manual effort is required to move the armature 25 to its attracted position. For this purpose, of course, the manually operable knob 28A is provided to allow the operator to move the armature 25 into engagement with the magnetizable core 26 against which the same is retained in attracted position only when both coils 22 and 23 are and remain properly energized.

After the armature 25 is thus magnetically retained against the core 26, the knob 38 is rotated to its "burner on" position (in which position the gas is allowed to escape also to the pilot burners 10A and 11A), in which case the passageways 36 and 20 are then opened to allow the escape of gas to the main burners provided, of course, that the condition responsive or control means 10C and 11C (FIGURE 6) are in condition to allow flow to the burners. Any gas escaping at any time from the main burners is ignited by the pilot flame. The knob 38 also has an "off" position and when the knob 38 is rotated to such position, the rotatable valve member 18 prevents flow of gas from the passageway 36 to both outlets 19 and 20, in which case the pilot burners are extinguished, the thermocouples cool sufficiently to allow the armature 25 to move to its non-attracted position, and thus the safety valve 14 returns to its closed position illustrated in FIGURE 1. The system may be placed in operation again, as explained above, using and requiring the manual reset operation which involves the application of manual force to the knob 28A to initially move the armature 25 against the core 26.

The present invention, of course, is not limited to furnaces since it is clear that other uses may be made of the same as, for example, in a gas range in which one burner may be in a broiler unit and another burner may be in an oven unit, where one can be ignited from the other resulting possibly in an explosion.

Also, the invention may be used on certain main burners, for example, the larger commercial type where a single pilot is insufficient to insure ignition and where delayed ignition may possibly result in explosion. Thus, the present invention is particularly useful where two pilot

burners are in use in a common combustion chamber and where it is desired to monitor operation of both pilot burners to insure reliability and fast ignition. Indeed, the present invention may be used in systems of this type where two output signals developed as, for example, by thermocouples, serve to control one common operating unit; and, indeed, instead of the common operating unit being operated from a thermocouple, the control or output signals may be derived from other sources. For example, a single device in accordance with the present teachings and structures incorporated herein may be operated by simultaneous application of output signals from two different electronic amplifiers which respond to the measurement of different physical conditions.

In accomplishing these functions, the structure of the electromagnetic means and particularly the core structure 26, its cooperating armature 25 as well as the mechanical mounting of such armature 25 is considered quite important.

The core 26 in FIGURES 1, 3, 4 and 9 is illustrated as being generally cylindrical with two parallel open-ended slots 50 and 51 machined in the same, the slots terminating a distance from the base to define two arcuate end legs 53 and 54 (around which corresponding preformed coils 22 and 23 are subsequently placed), a center leg 55 and a disc-shaped base portion 56.

The armature 25 is in the form of a disc having substantially the same diameter as core 26, and the abutting surfaces of such armature 25 and legs 53, 54 and 55 are preferably optically ground to assure a good even and uniform contact surface between the same.

The coils 22 and 23 are formed from insulated wire and, if desired, additional insulation in the form of insulation strips 60, 61, 62, 63, 64 and 65 may be used to insulately space the wire comprising the coils from the magnetizable core 26. This cylindrical core 26 may be stationarily mounted as shown in FIGURE 1 using a bolt 70 threaded into a central apertured portion 71 of the core member 26.

The armature 25, in the form of an apertured disc, is loosely mounted on the pin 72 which is secured in stem 28 with a bowed dished spring washer 76 between stem 28 and armature 25 to normally maintain the same as shown in FIGURE 7 with the countersunk surface 74 of armature 25 mating with a like conical surface defining the head of the pin 72. This means that the armature 25 may rock or pivot as shown in FIGURE 8 with respect to its retaining pin 72 and with respect to the core 26 to achieve certain advantages described later.

The coils 22 are "phased" so as to produce magnetic fields in "aiding" relationship as indicated by the arrows 89 and 81 in FIGURE 10, there being one coil for each thermocouple 10D, 11D as shown in FIGURE 10.

In cross section as illustrated in FIGURE 10, the magnetic core is generally E-shaped with windings 22, 23 placed on outer legs 53, 54. In the attracted position as illustrated, the windings 22 and 23 are fully energized by thermocouples 10D, 11D and center leg 53 is considered to carry a relatively small amount of magnetic flux since one of its ends is, of course, integrally formed with the base portion 56 and the other one of its ends is in engagement with the armature 25 through an intimate optically ground contact. In other words, substantially all of the flux is considered to flow through a path which includes, in turn, leg 54, base 56, leg 53 and armature 25, returning to leg 54 with little flux passing through center leg 53 since the magnetomotive force between the ends of such leg 53 under this condition is substantially equal to zero. The magnetic circuit described above is considered to at all times be operated along a substantially linear portion of its magnetization curve, i.e. in a region below the conventional "knee" in such curve, where magnetic saturation conditions do not exist.

The magnetic or mechanical pull in such instance may be represented by the equation

$$P = \frac{B^2}{72}$$

where P equals the pull in pounds per square inch, B is the flux density in thousands of magnetic lines per square inch and in this instance is substantially directly proportional to the current flowing in coils 22 and 23. These coils 22 and 23 have the same number of turns and thus produce the same number of ampere turns of flux in legs 53 and 54 which are of substantially identical cross-sectional area to achieve the same value of B in each leg 53, 54 whereby the pull on opposite ends of the armature 25 (in FIGURE 10) and more accurately the pull on the disc 25 is substantially uniform along that peripheral portion thereof which engages the legs 53, 54.

The armature 25, to remain in its attracted position against the force of compression spring 32, requires this simultaneous or joint energization of coils 22 and 23 in equal amounts; otherwise, the armature 25 is pulled away from its attracted position by the prestressed spring 32, the force of which is applied centrally to the armature disc 25 through a loose or semi-loose connection which allows pivotal movement of such armature as indicated in FIGURE 8.

Thus, should one winding 22 or 23 be de-energized or the current flow therethrough drop an appreciable amount as, for example, when its corresponding thermocouple 10D or 11D stops generating a sufficient voltage due, for example, to pilot flame outage, then a magnetic unbalanced condition results and the armature moves away from its attracted position. This unbalanced magnetic condition is now described on the assumption that the current flow through winding 22 has lessened a sufficient amount. When this occurs, the magnetomotive force across the ends of leg 53 becomes smaller and thus approaches the same value of magnetomotive force across the ends of the center leg 55 with the result that more of the flux developed by the other winding 23 now flows through the center leg 55 and a lesser amount flows through leg 53. The pull between leg 53 and the adjacent contacting portion of armature 25 lessens more than proportionally since the pull varies as the square of the flux density in accordance with the above formula. Thus, not only is the flux density lessened in the still active leg 54 but also there is a diversion of that flux produced in leg 54 and flowing into legs 53, 55 such that unbalanced forces with respect to the center of disc 25 exist on disc 25. This unbalanced force also aids in liberation of the armature from its attracted position, i.e. there is less likelihood that the armature will "stick" to the magnetizable core because of the existence of such unbalanced forces and the loose or semi-loose mounting of the armature on stem 28 which permits the armature to pivot as indicated in FIGURE 8 in response to such unbalanced force. This action results in much like a "prying" action in which the armature is "priced" away from its magnetizable core instead of all parts thereof being moved simultaneously equal distances from such core. While it is preferred to take full advantage of such unbalanced forces by thus pivotally mounting the armature, in some instances there may be a rigid connection between the armature and its stem.

Using the principles and teachings herein, the attraction of the armature may be controlled in accordance with the failure of one pilot flame in a group of more than two pilot flames. Thus, instead of only forming two coil cores 53 and 55 as in FIGURE 4, the core structure may be formed with three coil cores 90, 91 and 92 and a central core 93 having an equilateral triangular cross

section. In accordance with the above teachings it is understood, of course, that the cross-sectional areas of each leg 93, 91 and 92 are the same and that separate coils each having the same number of turns are placed on corresponding legs and that each coil is connected to a separate source of voltage exemplified above in the form of a thermocouple. The core of FIGURE 5 has associated therewith an armature mounted as in FIGURE 1 and the operation and functioning is substantially as described above to achieve the result that diminution of current flow through one of the plurality of coils below a certain level results in movement of the armature from its attracted position by a prestressed coil spring acting on a central portion of the disc armature.

In the three-coil arrangement these coils are "phased" as before, i.e. to produce flux which "aids" or flows in the same direction as that produced by the other coils.

In each case it is preferred, as shown in the drawings, that the cross-sectional area of the center leg, i.e. leg 55 in FIGURE 4 or leg 93 in FIGURE 5, be larger than the cross-sectional area of any one of the corresponding coil-carrying outer legs so that a greater diversion of flux results when the current through one of the coils is decreased. Preferably the core material in each instance is of the type having a relatively high initial magnetic permeability, i.e. a high permeability at the smallest current levels.

In some cases it may be desirable to shape the center leg as illustrated, for example, in FIGURE 11 by "flaring" the same outwardly in the direction of the armature, i.e. by making its cross-sectional area progressively larger the closer the same is to the armature. By doing so, the value of B is decreased and also the flux tends to be tangential to the plane of the armature instead of strictly perpendicular to the same, all of which has the effect of reducing the magnetic pull.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A device of the character described for controlling multiple devices, each having associated therewith a condition-responsive device comprising a single magnetizable core having a plurality of windings thereon, each connectable to a corresponding one of said condition-responsive devices, said core comprising a pair of outer legs and a center leg with a corresponding winding on a corresponding one of said outer legs, an armature engageable with both of said outer legs and with said center leg in the attracted position of said armature, means biasing said armature away from said core, said biasing means applying a biasing force to said armature at a central point thereon corresponding generally to the axis of said center leg, each of said windings being adapted to be connected to its corresponding condition-responsive device so as to produce a magnetic flux that traverses both of said outer legs with the flux so produced by one of said windings being in series-aiding relationship to the flux so produced by the other of said windings in each of said outer legs.

2. A device as set forth in claim 1 in which said armature is tiltably mounted with respect to said core at a point which is substantially in the center of the armature.

3. A device of the character described comprising a generally cylindrical core structure having formed therein outer legs and a center leg, separate windings on the corresponding one of said outer legs, the cross-sectional area of said outer legs being substantially the same and the number of turns of each of said windings being sub-

stantially the same, the cross-sectional area of said center leg being greater than the cross-sectional area of either one of said outer legs, an armature in the form of a disc having a diameter substantially equal to the diameter of said core and movable into attracted engagement with both said outer legs and said center leg, a stem having its axis extending generally as a prolongation of the axis of said center leg, means loosely mounting said armature on said stem for pivotal movement of said armature on said stem, means applying a biasing force to said stem in such a direction as to tend to move said armature away from its integrally attracted position, separate sources of current connected to corresponding ones of said windings and serving to maintain said armature in attracted position when each of said sources is effective, the attraction forces being smaller than the force exerted by said biasing means when only one of said current sources is rendered ineffective, each of said windings being connected to its corresponding source so as to produce a magnetic flux that traverses both of said outer legs with the flux so produced by one of said windings being in series-aiding relationship to the flux so produced by the other of said windings in each of said outer legs.

4. In a device of the character described, a core structure comprising a pair of outer legs and a center leg, a separate winding on each of said outer legs, a separate current source connected to a corresponding one of said windings, an armature attracted by said core structure and maintained in attracted position against said pair of outer legs and said center leg when each of said current sources is fully effective, means biasing said armature away from said core structure, and said core structure functioning to produce a force less than the force exerted by said biasing means when only one of said current sources is rendered ineffective, each of said windings being connected to its corresponding source so as to produce a magnetic flux that traverses both of said outer legs with the flux so produced by one of said windings being in series-aiding relationship to the flux so produced by the other of said windings in each of said outer legs.

5. A device as set forth in claim 4 in which said armature is pivotally mounted at a point corresponding generally to the center of said center leg and the force exerted by said biasing means is applied to the center of said armature.

6. In a multiple safety system of the character described, a single manually resettable valve means for controlling the flow of fuel to a pair of burners, each of said burners being associated with a thermocouple, an electromagnetic structure incorporating a single magnetizable core and a single armature movable relative thereto, means interconnecting said valve means and functioning to maintain said valve means in an operating position only when said armature is maintained in attracted relationship to said core, a plurality of coils wound on said core for energizing the same, said armature being maintained in attracted position only when all of said coils are energized, means for separately connecting each of said coils to a corresponding one of said thermocouples, and means movably mounting said armature such that the same may pivot on said core structure, said single core having a pair of outer legs and a center leg, one of each of said plurality of coils being wound on a corresponding one of said outer legs, each of said coils being connected to its corresponding thermocouple so as to produce a magnetic flux that traverses both of said outer legs with the flux so produced by one of said coils being in series-aiding relationship to the flux so produced by the other of said coils in each of said outer legs.

7. In a multiple safety system of the character described, a single manually resettable valve means for controlling the flow of fuel to a pair of burners, each of said burners being associated with a thermocouple, an electromagnetic structure incorporating a single magnetizable

core and a single armature movable relative thereto, means interconnecting said valve means and functioning to maintain said valve means in an operating position only when said armature is maintained in attracted relationship to said core, a plurality of coils wound on said core for energizing the same, said armature being maintained in attracted position only when all of said coils are energized, means for separately connecting each of said coils to a corresponding one of said thermocouples, and a valve-actuating element and means for loosely mounting said armature on said valve-actuating element such that the same may pivot on said core when one of said coils is de-energized, said single core having a pair of outer legs and a center leg, one of each of said plurality of coils being wound on a corresponding one of said outer legs, each of said coils being connected to its corresponding thermocouple so as to produce a magnetic flux that traverses both of said outer legs with the flux so produced by one of said coils being in series-aiding relationship to the flux so produced by the other of said coils in each of said outer legs.
